UNITED STATES PATENT OFFICE.

JOHN EBENEZER WRIGHT, OF BARROW-IN-FURNESS, ENGLAND.

FURNACE-DOOR FRAME AND DEAD-PLATE.

SPECIFICATION forming part of Letters Patent No. 761,746, dated June 7, 1904.

Application filed October 13, 1903. Serial No. 176,899. (No model.)

To all whom it may concern:

Be it known that I, JOHN EBENEZER WRIGHT, a subject of the King of England, and a resident of Barrow-in-Furness, in the county of 5 Lancaster, England, have invented certain new and useful Improvements in Furnace-Door Frames and Dead-Plates, of which the following is a specification.

The invention refers to the furnace-door frames and dead-plates of furnaces subjected to great heat, such as those of steam-generators having brick-lined furnaces and in which the draft, whether artificial or natural, is relatively great; and it has for its object and effect to provide improvements by which the rapid overheating and burning away of portions of these door-frames and dead-plates exposed to the excessive heat is prevented or diminished.

It is found in practice that in brick-lined furnaces of steam-generators where the draft is great (such as in water-tube boilers) the metal arch or support which carries the brickwork above the stoking-doorway gets very hot and 25 unable to bear the weight of the brickwork (which is also very hot) above it, especially after it is burned away. According to this invention this is prevented by extending the doorway-frame inward under the brickwork lining at the front of the generator and making it hollow and open at the front and making the sides and dead-plate hollow and connecting all these hollow chambers with the ash-pit below the bars, so that the whole or a considerable portion of the air supplied to the ash-pit may pass by way of these air-channels from the furnace-door frame. This is illustrated in the accompanying drawings, in which—

Figure 1 is a longitudinal section. Fig. 2 is a plan in section taken at the line xx , Fig. 1; and Fig. 3 is a plan of the portion of the dead-plate separate, showing the construction wherein the frame and the dead-plate are made separately and detachable, while Fig. 4 is a longitudinal section, Fig. 5 a front view, and Fig. 6 a plan, half in section, showing the construction wherein the dead-plate and frame are in one.

Referring to the drawings, a represents the ordinary metal casing of the front of a steam-

generator furnace. b is the brickwork inside it. c represents the fire-bars, and d is the ash-pit.

e designates generally the furnace-door frame, and f designates generally the dead-plate between the door and the front ends of the fire-bars c , and g is the furnace-door.

The furnace-door frame e consists of three portions—namely, a roof or arched portion h open for its entire length on the outside of the furnace at i and closed at the inner end, and two hollow side portions j , communicating directly with the interior of the arch h at their upper ends and with the sides of the hollow dead-plate f at their lower ends, partial diaphragms k being cast in the sides j and on the opposite sides of it to give the air a longer and zigzag course through them. The front edge of the upper plate forming the roof of the hollow dead plate f rests on the upper face of an angle-bar l , and the front of the lower plate or floor of the hollow dead-plate f rests on the upper face of an angle-bar m inside the casing a , these two bars being fastened in place to the casing by bolts n and the hollow plate f being held in position by the screw-studs o .

The upper plate of the dead-plate f has an opening p at each side—that is, it is perforated at p —into which the lower ends of the sides j of the frame fit, and these lower ends being open direct communication from the sides with the interior of the dead-plate f is effected.

The entrance of air to the ash-pit d by way of the hollow door-frame e and dead-plate f is controlled by a damper q , mounted and adapted to slide on the under side of the dead-plate and over the opening r in the back end of the floor of the dead-plate, it being operated by a rod s , connected with it and extending through the front case a and provided with a handle t on its outer end.

In the cases shown the dead-plate f is divided longitudinally by a partition, forming it into two chambers, in connection with each of which a separate damper q and operating-handle t are employed.

In action the whole or a greater or less amount of the air required for combustion is 100

passed into the arch *h* of the door-frame *e* through the open front at *i* extending across it and down the hollow sides *j* into the two portions of the dead-plate *f* and thence by way 5 of the openings *r* into the ash-pit, with the result that the metal is kept below the burning-point—that is, below red heat—and its strength for supporting the brickwork *b* is in consequence retained; but the cooling effect may be 10 further increased by admitting jets of steam into the front portion *i* along with the air.

By the construction shown in Figs. 1 to 3 when the dead-plate *f* or the frame *e* becomes worn out or broken the one or the other can 15 be renewed by the detachable construction set forth.

In the modification shown in Figs. 4 to 6 the dead-plate *f* and frame *e* are cast in one, the dead-plate being inclined, and the valves 20 *q* work in connection with the opening *r* at the back end of the dead-plate. In other respects the construction is the same practically as that set forth with reference to Figs. 1 to 3.

Having now particularly described my invention, what I claim as new, and desire to secure by Letters Patent, is—

1. In a furnace, the combination with the casing *a* of the furnace and brick lining *b* with- 25 30 in same, of the door-frame *e*, comprising a hollow roof *h* on which the bricks *b* are sup-

ported, and open in the front at *i* to the outside atmosphere, and closed at the inner end; hollow sides *j* having both sides closed and in free communication with the hollow roof *h* 35 at their upper ends; and a hollow dead-plate *f* connected with the lower ends of the hollow sides *j*, and having its interior communicating with the said lower ends, and a discharge-opening *r* in the inner end of the dead-plate *f*; substantially as set forth.

2. In a furnace, the combination with the casing *a* of the furnace and brick lining *b* with- 40 in same, of the door-frame *e*, comprising a hollow roof *h* on which the bricks *b* are support- 45 ed, and open in the front at *i*, to the outside atmosphere, and closed at the inner end; hollow sides *j* in free communication with the hollow roof *h* at their upper ends; a hollow dead-plate *f* connected with the lower ends of 50 the hollow sides *j*, and having its interior communicating with the said lower ends, and a discharge-opening *r* in the inner end of the dead-plate *f*; and a damper *q* adapted to cover and uncover the opening *r*; substantially as 55 set forth.

In witness whereof I have hereunto set my hand in presence of two witnesses.

JOHN EBENEZER WRIGHT.
